Inventor:
Henry A. Van Houten,
By his Attorney, *McCarton*.

UNITED STATES PATENT OFFICE.

HENRY A. VAN HOUTEN, OF NEW ROCHELLE, NEW YORK.

VISIBLE INDEX.

Application filed June 3, 1925. Serial No. 34,506.

To all whom it may concern:

Be it known that I, HENRY A. VAN HOUTEN, a citizen of the United States, and a resident of New Rochelle, in the 5 county of Westchester and State of New York, have invented new and useful Improvements in Visible Indexes, of which the following is a specification.

This invention relates to indexes or files, 10 and it has particular reference to a visible index comprising a plurality of record cards which, normally, are held in overlapped relation so that only the marginal portions thereof are exposed to view. The 15 invention also has special reference to a system of this kind in which each card is held flatwise on a support, preferably the ordinary filing folder, by a tongue or tongues on the card, which tongues are outwardly directed and are so constructed and applied as to provide an interlocking feature which insures uniform visibility.

A further object is to slidably secure the 20 cards to the folder by means of outwardly directed tongues positioned near the extreme edges of such cards, so that the resistance of the card to tearing when reference is made thereto or notations are made thereon and the flexing of the card without 25 danger of tearing off the tongues is facilitated.

A further object of my invention is to 30 provide a visible filing system that can be manufactured with the minimum of expense and simplicity and also making possible its use in the offices of concerns maintaining record cards numbering into the millions at a minimum of expense for new equipment for filing the same.

40 A further object of my invention is to provide a visible filing system whereby only two members are used, namely, a support and cards, which result in the cards being mounted upon said support in such a manner as to allow an absolutely flat support for the writing surface on the cards without necessitating the removal of same from the support when it is desired to make notations thereon.

45 A further object of my invention is to provide a means whereby only two members need be used, namely, an ordinary correspondence filing folder or other size filing folder and cards.

50 A further object of my invention is to provide a flexible filing system whereby

said folders to which cards have been attached as described can be removed from a file such as four-drawer filing cabinets, tub desks, or other filing devices and rolled up 60 either one way or another leaving the cards intact in visible relation.

With these and other objects in view, the invention consists in the construction, arrangement and combination of the various parts of my device, whereby the objects contemplated are attained, as hereinafter more fully set forth, pointed out in my claims, and illustrated in the accompanying drawings, in which

70 Figure 1 is a front view of one of the index elements or cards,

Fig. 2 is an end view of the card shown in Fig. 1,

Fig. 3 is a front view of a series of cards 75 such as shown in Fig. 1 mounted upon one leaf of a folder,

Fig. 4 is a back view of the cards and folder shown in Fig. 3 and

Fig. 5 is a view of the card similar to 80 that shown in Fig. 2 but showing a modification of the indicating element.

Similar reference characters refer to like parts in the figures.

Referring to the drawings, 1 indicates an 85 index element or card which may be made of any suitable material preferably cardboard. Upon the card outwardly directed tongues 2 are formed near the sides of the card 1 and having terminal portions 3 for 90 engaging the narrow slits 4 formed in the folder 5 shown in Fig. 3. The tongues 2 are separately formed and widely spaced so as not to weaken the card further than is absolutely necessary as well as to facilitate the flexing of the card with respect to the folder without danger of tearing or shearing off the tongues when it is desired to insert a card in the support or remove the same therefrom. By forming the engaging 100 portions 3 outwardly directed, the card is supported at widely separated points by the entire areas immediately adjacent the base of the tongues, so that any turning movement with relation to the folder is eliminated.

105 The card 1 is also provided with a horizontal slot 6 extending almost across the entire length of the card and in close proximity to the top of the card. An indicator 110 7, preferably of celluloid, extends through the narrow slit 6 and over the top of the

card so as to form a band slidable along the top portion of the card as shown in Figs. 1 and 2. An aperture 8 may be provided in the front portion of the indicator 5 7 so that the notations 9 upon the upper portion of the card may be visible therethrough.

In Figs. 3 and 4 is illustrated the method by which a plurality of cards are mounted 10 upon an ordinary folder. As mentioned above, parallel slots 4 are provided in one leaf of the folder or other support. The engaging portions 3 of the tongues 2 are bent backward and engage in the slots 4 for supporting the card 1. A second card is inserted above the first card mounted upon the folder and the downward movement of the second card is limited by the tongues of the first card as shown in Fig. 3. In this manner a 15 series of cards can be mounted upon the folder 5 in such manner that the upper portion of each card overlaps the preceding card, rendering the upper portions of all the cards visible to the user.

25 While I have illustrated a slotted folder for supporting a series of cards in the manner herein described, there may be certain installations in which it would be preferable to support one or more master cards in a 30 folder or other support in the same manner above described as each card is supported, and each master card would in turn be vertically slotted to receive a series of cards in the manner that such series is supported 35 herein by the folder. In some cases also the master card carrying the series of cards may be filed without being mounted in a folder or on another support.

Various changes may be made in the construction and arrangement of the invention 40 above set forth without departing from the real purpose and spirit thereof, and it is the intention to cover by the following claims, any modified forms of structure or use of 45 equivalents, which may be reasonably included within their scope.

As shown in Figs. 2 and 3 slits 4 in the supports are of just sufficient width to receive

the tongues of the cards to be filed and correspond substantially to the thickness of the 50 material of the cards 1, although obviously the same may be a little narrower than the thickness of the material of the cards 1 or a trifle wider, but they should not be of such a width as to prevent the support serving 55 as a substantially continuous surface to support the card in a flat plane when it is desired to make notations thereon without removing the same from the support.

Having thus described my invention, what 60 I claim and desire to obtain by United States Letters Patent is:

1. In an index or file, a support having narrow slits in substantial parallelism with each other, cards adapted to be mounted upon 65 said support in overlapped relation, tongues separately formed and widely spaced upon said cards within the periphery of each card and including portions outwardly directed towards the sides of said card for engaging 70 the narrow slits in said support whereby the flexing of said card without danger of tearing off the tongues is facilitated.

2. In an index or file, a support having narrow slits terminating intermediate the 75 top and bottom respectively of said support, cards adapted to be mounted upon said support in overlapped relation, tongues separately formed and widely spaced upon said cards and disposed within the periphery of 80 each card and including outwardly directed portions for engaging said narrow slits whereby the flexing of said card without danger of tearing off the tongues is facilitated, said slits being of insufficient width 85 to prevent the support from serving as a continuous supporting surface for the card when the same is mounted therein and it is desired to make notations thereon, and the entire surface of a support lying substantially in but a single plane when the card is mounted thereon.

Signed at New York in the county and State of New York this first day of June, 1925.

HENRY A. VAN HOUTEN.
